UNITED STATES PATENT OFFICE.

CARL O. HEDSTROM, OF SPRINGFIELD, MASSACHUSETTS.

CONVERTIBLE BICYCLE AND TANDEM FRAME.

No. 895,753.

Specification of Letters Patent.

Patented Aug. 11, 1908.

Application filed March 28, 1907. Serial No. 365,135.

To all whom it may concern:

Be it known that I, CARL OSCAR HEDSTROM, a citizen of the United States of America, residing at Springfield, in the county of 5 Hampden and State of Massachusetts, have invented new and useful Improvements in Convertible Bicycle and Tandem Frames, of which the following is a specification.

My present invention relates to the construction of motor cycles and has as a particular object the conversion of an ordinary motor cycle into a tandem.

It is sometimes very desirable to have an attachment or complementary frame that can be readily attached to a motor cycle whereby the same can be converted into a tandem; the complementary frame being provided with a saddle and front wheel so that when the same is substituted for the front fork of the 20 ordinary motor cycle a tandem is produced.

Another object is to provide the complementary frame with means for engaging the crank-hanger of the motor cycle; a further object is to provide the complementary frame 25 with a flexible foot-rest and also with means to assist in steering the machine.

This invention relates to the construction shown in my prior United States Letters Patent dated January 29, 1907 No. 842,833, 30 to which reference will be made in the body of the specification.

Further objects of the nature and construction of the invention will be fully set forth in the specification.

35 In the drawings forming part of this application,—Figure 1 is a side elevational view of the motor cycle with the complementary frame or attachment in place. Fig. 2 is a plan view of a detail construction showing the manner of securing the complementary frame to the crank-hanger of the motor cycle. Fig. 3 is a side elevational view of the detail structure shown in Fig. 2, a portion of the same being in section. Fig. 4 is a detailed 40 view of the foot-rest showing the manner of mounting the same in the lower end of the attachment, while Fig. 5 is a perspective view of the foot-rest detached from the frame.

50 The framework of an ordinary motor cycle is usually of a diamond shape construction as designated by the reference letter *a*.

In order to convert the motor cycle into a tandem it is necessary to provide some means 55 for lengthening the framework of the machine, and in order to accomplish this result,

I have found it convenient to replace the ordinary front fork of the machine, which carries the forward wheel, and substitute therefor a complementary frame which is provided 60 with a saddle and steering mechanism and is so constructed as to be readily and rigidly secured to the crank-hanger of the motor frame *a*.

The complementary frame is provided with 65 a horizontal bar *b*, a brace element *c*, and parallel uprights *d* and *e* of suitable tubular material. These uprights are further braced and connected by means of the horizontal cross-bars *f*, the lower ends of the uprights 70 being connected by means of the inclined bar *g* which extends into the horizontal portion *h*, as clearly shown. This bar *g* is connected to a steering head *i*.

j designates an inclined brace-bar extending 75 between the steering-head *i* and upright *e*.

Mounted within the upright *d* is a suitable steering-rod or shaft *k* that extends through the steering-head *m* and the upright *d*. The 80 details of this construction are clearly shown in my above referred to United States Letters Patent No. 842,833 and need not be specifically described herein.

The upper end of the upright *e* of the complementary frame carries a saddle *e*¹ mounted 85 on the post *e*² in the usual manner.

A suitable pulley or arm *n* is mounted on the lower end of the shaft *k* for receiving the wire cord *o* that passes under the anti-friction roller *p* and over the anti-friction roller 90 *r* to another pulley that is mounted on the steering-shaft *s* of the complementary frame and designated at *t*. The two handle-bars *u* and *v* can therefore move in unison so that 95 each rider can assist in steering the vehicle when in use.

The bar *b* is attached to the crank-hanger, portion *w* of the motor frame by means of the construction shown in Figs. 2 and 3, and is 100 the same construction as that described in detail in Figs. 1, 4, and 5 of my prior patent heretofore referred to.

It will therefore be seen that the tandem or complementary frame can be readily attached to and removed from the motor frame *a* of the motor cycle by merely replacing the usual front fork with the steering-shaft *k* that is mounted in the complementary frame and attaching the horizontal bar *b* to 105 the crank-hanger *w*.

Referring to the structure shown in Fig. 4

in which a detailed view of the foot-rest is shown, *x* designates a plunger reciprocally mounted in the upright *e* and carries at its upper end a guiding piston or element *y* that is secured to the plunger *x* by means of the nuts *z*. Into the lower end of the upright *e* is threaded a plug 2 through which the plunger *x* can freely move. The lower end of the plunger is provided with a head 3 which is 10 pivotally connected to the foot-lever 4 and is pivotally connected to a depending lug 5 on the horizontal part *h* at the point 6. The forward end of the lever 4 is provided with 15 pedals 7. Mounted between the plug 2 and the piston *y* is a coiled spring 8 that is normally under compression so that the lever 4 is constantly elevated. In order to prevent the head 3 from striking the plug 2, I place a buffer spring 9 between the plug 2 and the 20 head 3 which will absorb the blow when the foot is removed from the pedals 7, as readily understood.

What I claim, is:—

1. In combination, a bicycle frame, a complementary frame therefor, a foot-rest forming 25 a part of the complementary frame and in-

cluding a tubular upright member as *e*, a horizontal member as *h*, a piston located in the upright member, a foot-lever pivoted to the horizontal member, means located between the piston and foot-lever to normally retain said lever in an elevated position, and means to cushion the foot-lever at the limit of its upward movement. 30

2. In combination, a bicycle frame, a complementary frame therefor, a foot-rest mounted thereon and elastic means for exerting an upward movement on the foot-rest. 35

3. In combination, a bicycle frame, a complementary frame, a foot-rest pivoted thereto, and means for cushioning said foot-rest. 40

4. In combination, a bicycle frame, a complementary frame, a foot-rest pivotally connected thereto, a plunger connected to the foot-rest, and elastic means carried by the plunger whereby an upward movement is 45 imparted to the foot-rest, as described.

CARL O. HEDSTROM.
